UNITED STATES PATENT OFFICE.

LOUIS STEINBERGER, OF BROOKLYN, NEW YORK.

MOUTHPIECE.

1,160,545.

Specification of Letters Patent. Patented Nov. 18, 1915.

Application filed February 10, 1912. Serial No. 876,872.

To all whom it may concern:

Be it known that I, LOUIS STEINBERGER, residing at Brooklyn, in the county of Kings and State of New York, have invented certain new and useful Improvements in Mouthpieces, of which the following is a specification.

This invention relates to sound transmitting devices, as exemplified in the transmitter of a telephone set, for instance, though there are other devices in which the invention may be embodied.

Among the objects of my invention are: I. To improve the acoustical properties of sound transmitting devices of the general character referred to. II. To provide a telephone transmitter, or other sound transmitting device, of such construction that the likelihood of chipping or breaking away of exposed portions of the article is minimized. III. To give to certain exposed portions of a device of the kind referred to such a form that the complete structure will have no portion extending out from the general outer surface of the device, and will have a minimum of abrupt corners, especially in those parts which ordinarily face the operator; hence it will be free from lodging places for disease germs, and may readily be cleansed when necessary or desirable. IV. To provide a device of the kind referred to, in which certain readily removable portions are given such conformity that glass, porcelain or the like material may be employed with good effect; when such materials are employed, the device becomes hygienic in the best sense of the word, since the removable portions may be boiled in water or other liquid, or cleansed in disinfecting solutions or the like. V. To provide, more specifically, a mouthpiece for telephone transmitters, which is simple and economical to manufacture from any appropriate material, which is desirably sanitary and very durable, and which is, without, graceful in appearance. VI. To provide, in a telephone transmitter, a unitary member in the form of a solid block, which serves both as a cap-plate and mouthpiece, and which may entirely cover the diaphragm and clamps the latter in position. VII. To provide, in a telephone transmitter, a cap-plate which entirely covers the diaphragm and forms therewith a distributing chamber whose greatest width is at the center, gradually constricted outwardly.

Other objects and aims of the invention,

more or less broad than those stated above, will be in part obvious and in part specifically referred to in the course of the following description of the elements, combinations, arrangements of parts, and applications of principles constituting the invention; and the scope of protection contemplated will appear from the claim.

In the accompanying drawings, which are to be taken as a part of this specification, and in which I have shown merely illustrative embodiments of the invention; Figure 1 is a plan or end view of a telephone transmitter; including my invention; and Fig. 2 is a sectional view which illustrates the application of my invention in a telephone transmitter.

It will be noticed that in the drawings I show my invention as visualized in a telephone transmitter cap and mouthpiece of peculiar conformation, and in the correspondingly formed transmitter casing; and the ensuing description will be specific to such apparatus. As before stated, this device is merely typical of a class, and I contemplate that my claim shall be construed in the light of this statement. Proceeding accordingly, and referring to the numerals on the drawings, 4 indicates a generally circular member, preferably a solid block, which is provided centrally with an opening 5, through which sound waves may pass. If preferred, the inner end of this opening 5 is partly closed by a perforated web 6, the opening 5 having its smallest cross-sectional area at its inner end, and gradually increasing in diameter until the curve of its walls merges into the outer surface of member 4 about the opening 5. The inner surface of the web 6 is substantially flush with the surface of the inner side of the mouthpiece so as to present no shoulders inside the web. The edge portion of the block is formed into a circumferential plane offset or edge 7, which provides an attaching portion for the block; and the inner face of member 4 slopes downwardly from all sides to the center, i. e., to the opening 5. The outer face of member 4 comprises an outwardly convexed preferably spherical surface 8, symmetrical with respect to the center of member 4, so that the longest line from the inner to the outer side of member 4 is through the center thereof, the walls of the opening 5, as already stated, merging into said spherical outer surface, without any abrupt lines.

Such a member as has been described is

intended to be supported by a transmitter casing or the like, into which sound waves are transmitted through the opening 5. In Fig. 2 I show the member 4 applied as the 5 cap and mouthpiece of a transmitter casing 9. Here the end of the casing provides an annular seat 10, and a diaphragm 11 extends across the casing, resting upon the seat 10, and the diaphragm is clamped in 10 position between the seat 10 and the offset member 7, when the block 4 is laid over the end of the casing as shown.

As an example of means for holding the 15 block and casing in assembled relation, I may provide a ring member 12 of such diameter that it may be dropped over the block and seat upon the ledge 7, and having a depending interiorly threaded annular flange 14 which is adapted to engage the 20 correspondingly threaded circumference of the casing at the end thereof. Obviously, I might secure the parts together in other ways, and the method and means described are merely illustrative. The transmitter casing 25 will of course contain the necessary devices (not shown) for utilizing the vibrations which may be set up in the diaphragm.

By reason of the sloping surfaces of the 30 inner face of member 4, which are opposed to the plane surface of the diaphragm, there is formed a circular chamber between the diaphragm and the member 4, which chamber is of greatest width at its center and gradually constricted outwardly from the 35 center. By this arrangement and its combination with the form of the opening 5, as well as by the general construction, the acoustical properties of the device are much improved over what they would be if the 40 inner surface of the member 4 were made parallel with the outer surface of the diaphragm.

It will be evident that such a device as I have described will attain, among others, 45 the objects set out above. The member 4 is simple and economical to manufacture, and may easily be made of any appropriate material. The device may readily be secured to a supporting or body member in 50 a simple way, and at small expense; when it is in place on its support there is no extreme projection of any part, so that liability of breakage is practically obviated, besides which the member 4, being substantially 55 a thick, solid block, is inherently more durable than the relatively thin, frail, mouthpieces now generally used. Where the device is embodied in a transmitter, it provides in a single piece a cover plate 60 and a mouthpiece covering the entire surface of the diaphragm, and clamping the diaphragm in position. By reason of the

peculiar form of the inner face of the member 4, and also that of the entire device, the acoustical properties of an instrument with 65 which it is included are greatly improved. And finally, the device is most sanitary, since it affords few lodging places for germs, and is, owing to its outward form and its ready detachability, readily cleansed, 70 *in situ* or when removed.

Where the device is not made up of porcelain or the like, it may be of the material well known in the art as Electrose, or of some other suitable, preferably insulating, 75 material. The form shown, in which there is no threaded connection between the casing and block, is particularly well adapted for porcelain or glass embodiments, which are threaded but with difficulty, and when 80 threaded are very liable to be broken when the screw connection is made.

As many changes could be made in the above construction and many apparently 85 widely different embodiments of this invention could be made without departing from the scope thereof, it is intended that all matter contained in the above description or shown in the accompanying drawings 90 shall be interpreted as illustrative and not in a limiting sense. It is also to be understood that the language used in the following claim is intended to cover all of the generic and specific features of the invention herein described and all statements 95 of the scope of the invention, which as a matter of language, might be said to fall therebetween.

Having thus described my invention, what I claim as new and desire to secure by Letters Patent is:

A mouthpiece for a telephone transmitter casing comprising, an annular disk like member of a diameter substantially the same as the exterior diameter of the transmitter casing, and being arranged over the end of the casing, said member being concaved on its inner surface and convexed on its outer surface, and having an outwardly flaring aperture centrally therethrough, an integrally formed perforated web across the inner end of the aperture flush with the inner surface of said member, a separately formed annular collar rotatably mounted upon the periphery of said member, and means whereby rotation of said collar about said member will clamp said member against the transmitter casing.

In testimony whereof, I affix my signature in the presence of two witnesses.

LOUIS STEINBERGER.
